UNITED STATES PATENT OFFICE.

TOM B. MYERS, OF NEWPORT, RHODE ISLAND, ASSIGNOR TO THE GOVERNMENT OF THE UNITED STATES.

TORPEDO.

Application filed August 9, 1920. Serial No. 402,086.

To all whom it may concern:

Be it known that I, TOM B. MYERS, a citizen of the United States, residing at Newport, Rhode Island, have invented new and useful Improvements in Torpedoes, of which the following is a specification.

This invention relates to improvements in torpedoes and more particularly to improvements in that part generally known as the pistol for igniting the burners in the combustion flask when the torpedo is fired.

This invention may be designated more properly as being a low pressure air pistol as distinguishing from the high pressure operated pistols heretofore used.

One of the objects of the present invention is to provide a simple and practical pistol of the above general character which will be thoroughly reliable and efficient in use and operation.

A further object is to provide an improved pistol applicable to either a single or double fuse and one which will be self cocking and inert up to the moment of firing wherefore premature or accidental firing is impossible.

A further object is to provide a pistol of the above character of simple design and having its parts so constructed and arranged as to prevent leakage of air during the operation.

Other objects will be in part obvious and in part hereinafter pointed out.

In order that a clearer perception of the present invention may be had a sheet of drawings is herewith attached forming part of this enclosure and in the several figures of which corresponding reference characters denote corresponding parts, in which,

Figure 1, is a vertical, sectional view showing the device in normal position.

Figure 2 is a similar view showing the parts in position just prior to the firing operation.

By way of explanation it may be stated that modern automobile torpedoes are provided with a combustion flask into which compressed air and water are admitted and adjacent the water inlet is a burner through which alcohol or other suitable combustion material is sprayed. This alcohol is ignited as the torpedo is launched by means of the pistol forming part of this invention and the burning alcohol converts the water into steam which mixes with the

compressed air and passes from the combustion flask to the turbines for driving the torpedo.

All of these principles are well known to those skilled in the art and further illustration or description thereof is believed to be unnecessary. It is sufficient to state that the present device is adapted to be threaded through the wall of the combustion flask adjacent the burner for the purposes above set forth.

Referring now to the drawings, a main body member 5 is provided with threads 6 for engagement with the walls of the combustion flask. The upper part of this body member is threaded at 7 to receive a cylindrical member 8 carrying and supporting three valves 10, 11 and 12 respectively. The member 10 rests against a ring 13 in the lower part of the member 8 and is provided with a firing pin 9 adapted to coact with the cap not shown. The central valve 11 is adapted to coact with its seat when in the position shown in Figure 2 while the upper valve 12 normally rests upon seat 15 as shown in Figure 1. Interposed between the valve 11 and valve 10 is a cocking spring 16 while a holding spring 17 surrounds a stem 18 of the valve 12. One end of this spring 17 coacts with a collar 20 beneath the valve 12 while the opposite end bears against a washer 21 supported by pin 22 on the valve stem.

It will be noted that the valve 10 is provided with a passage 23 which allows air to pass from one side to the other as will hereinafter be explained in connection with an outline of the operation of this device.

This pistol is designed to receive air pressure from the combustion flask or pot in which it is inserted. The air pressure which is comparatively low at first and gradually increases acts to force the pin or valve upwardly from the position shown in Figure 1 to that shown in Figure 2. This pin is vented and is not a machine fit within the lower part of the cylindrical member 8 consequently air passes into and acts on the valve 11 also forcing it up against its seat 14. Before this valve 11 closes, however, the air has passed and escapes through the upper or relief valve 12 which, in the meantime, has been gradually approaching the position shown in Figure 2. The passage of air through these three working parts prevents cushioning during the compression of the

firing spring 16 and the relief valve spring 17. As soon as the valve 11 closes air pressure on the opposite sides of the firing pin 9 are equalized by means of holes in the walls of the pistol above the firing pin as indicated at 23 and the firing spring is, therefore, free to drive the firing pin downwardly without pressure interference. The air pressure is utilized to cock the pistol and 10 compress the firing spring, this air pressure being subsequently neutralized at the moment of firing by the closing of valve 11. This neutralization of the pressures, of course, permits this firing spring 16 to expand instantly with sufficient force to ignite the cap engaged by the firing pin 9 carried by the valve 10.

While the operation has been described with relation to its successive steps and 20 terms have been used which might imply a slowness of operation for the sake of clearness, it is, of course, to be understood that the complete operation of the entire device is almost instantaneous.

25 From the above it will be seen that the present invention provides a simple and practical pistol having relatively few parts which may be inexpensively manufactured and assembled and the simplicity of design 30 is especially to be noted in connection with its safeness and reliability.

Without further analysis, the foregoing will so fully reveal the gist of this invention that others can by applying current 35 knowledge readily adapt it for various applications without omitting certain features that, from the standpoint of the prior art, fairly constitute essential characteristics of the generic or specific aspects of this invention, and, therefore, such adaptations should and are intended to be comprehended within the meaning and range of equivalency 40 of the following claims.

What I claim is:

45 1. In a device of the character described, in combination, a valve carrying member, a plurality of valves and valve seats associated therewith, one of said valves being subjected to pressure in the combustion 50 flask to close a second valve, said second

valve being associated with the third valve to open the same as said second valve approaches closed position, said device being provided with means for equalizing the pressure on the opposite sides of said first mentioned valve and a firing spring associated therewith adapted to move the first mentioned valve to firing position after the pressure has been equalized.

2. In a device of the character described, in combination, a valve, a firing pin associated therewith and means whereby air pressure may pass from one side to the other of said valve, a firing spring engaging said valve, a second valve coacting with said firing spring adapted to be closed as said firing spring is compressed on movement of said first mentioned valve whereby when said second mentioned valve is closed the pressure on the opposite sides of said first mentioned valve becomes equalized and permits said firing spring to operate.

3. In a device of the character described, in combination, a valve carrying member, a second valve adapted to be closed on movement of said member and a relief valve adapted to be opened during the closing of said second mentioned valve.

4. In a device of the character described, in combination, a main valve, a firing pin associated therewith, said valve having a passage whereby pressure may be equalized upon opposite sides of said valve, a secondary valve, a compression spring acting between the adjacent surfaces of said valves, and a normally closed spring actuated relief valve, whereby a relative movement of the main valve causes a closing of the second valve and an opening of the relief valve thus permitting equalization of pressure on opposite sides of the main valve to restore said first mentioned valve to its former position thus bringing the firing pin into operation.

Signed at Newport, Rhode Island, this 95
13 day of March, 1920.

TOM B. MYERS.
